UNITED STATES PATENT OFFICE.

FREDERICK MARKWICK, OF FALLS, PENNSYLVANIA.

ANTISKIDDING LINK.

Application filed October 7, 1927. Serial No. 224,628.

The invention relates to improvements in anti-skidding and traction attachments for automobile wheels and has reference more particularly to a link of novel form which 5 may be related in any of a great number of ways, with other links so as to effectively prevent skidding and give efficient traction, regardless of how slippery the roadway or other surface may be.

10 It is the object of the invention to provide an exceptionally simple and inexpensive link of the class set forth which may be readily connected with other links and then closed or substantially closed to prevent 15 accidental disconnection, although permitting sufficient opening to remove the link whenever it is advisable to replace it with a new one.

With the foregoing in view, the invention 20 resides in the novel subject matter herein-after described and claimed, the description being supplemented by the accompanying drawing.

Figure 1 is a fragmentary plan view of 25 tire chains embodying a plurality of the improved anti-skidding links.

Fig. 2 is a fragmentary elevation looking in the direction of the arrow A of Fig. 1.

Fig. 3 is an enlarged transverse sectional view through one of the anti-skidding links, 30 taken on line 3—3 of Figs. 1 and 2 and for sake of clearness, omitting the connected link which would in reality appear behind the plane on which the view is cut.

Fig. 4 is a fragmentary plan view showing a somewhat different form of link construction and illustrating a plurality of the anti-skidding links connected directly with each other and disposed in a channel in the 40 tread of a tire.

Fig. 5 is a transverse sectional view substantially on line 5—5 of Fig. 4.

Fig. 6 is a plan view of an anti-skidding link very similar to those shown in Figs. 4 45 and 5 but illustrating it connected with ordinary chain links, this construction being particularly adaptable for use on anti-skid chains for busses and trucks.

The form of construction shown in Figs. 50 1, 2 and 3 will first be described. The numerals 7 denote anti-skidding links constructed in accordance with the invention. Each of these links is preferably formed from a single short piece of metal rod 8 of 55 desired diameter. The ends of this rod are formed with return bends 9 providing two

hooks whose bills 10 extend longitudinally toward the opposite ends of the links. At the ends 11 of the bills 10, the rod ends are bent outwardly upon and extend longitudinally of said bills, providing elongated calks 12 for engagement with a roadway or the like, these calks being preferably ground or otherwise sharpened as clearly shown in Figs. 1 and 3.

Transversely, the link 7 is of substantially V shape, with one of the hooks 9 and its calk 12 occupying one side S of the V (Fig. 3), with the other hook 9 and its calk 12 occupying the other side S' of the V, and with the substantially central longitudinal body portion 8 of the link disposed at the apex of the V. The hooks 9 constitute means for connecting the ends of the link with additional links and it will be observed that they are spaced inwardly from a common plane P at which the road-engaging edges of the calks 12 terminate. This relation will be understood from Figs.

2 and 3. In the former, the calks 12 are both shown terminating at the plane P and while this same relation exists in Fig. 3, only one of the calks is shown extending to said plane, as it is the portion of the other calk which is cut away in this view, 85 that extends to said plane.

The links 7 may be used in any desired number and in any advantageous relation with other links either of the same construction or of any other construction.

In Figs. 1 and 2, two of the links 7 are embodied in each cross chain C of an otherwise conventional tire chain, whose side chains SC may of course be constructed and connected in any desired manner. Each 90 cross chain C may well embody a plurality of links of ordinary form connected with the outer ends of the links 7, and the inner ends of these links may be connected by an oval or other desired link L.

In Figs. 4 and 5, the links 7^a are of substantially the same construction as the links 7, but instead of forming the calks 12^a of triangular shape in transverse section, they are rectangular. They nevertheless 105 present sharp edges for contact with the roadway to prevent skidding and to give ample traction. The bills 10^a in this form of construction converge sufficiently with the elongated body portion 8^a, to prevent adjacent links from being accidentally unhooked 110 from engagement with each other. This

same construction exists in the form of the invention first described.

In Figs. 4 and 5, a plurality of the hooks 7^a are connected directly with each other 5 to provide a continuous chain which occupies a peripheral groove G extending around the circumference of a tire T. No claim is herein made to the disposition of the chain in the groove G, nor to the tire construction, 10 but Figs. 4 and 5 serve to illustrate another of the many ways in which the improved anti-skidding link may be employed. If desired, instead of using the links 7^a in the relation shown in these views, links 7 could 15 of course be employed and in fact any other form of the invention could be embodied in the links of the chain, and it will be understood that such chain could be formed either totally of the improved links or could 20 only embody them at intervals.

Fig. 6 discloses a construction which is preferable on heavy duty chains such as those used on motor trucks and busses. In this view, one of the improved links 7^b 25 is shown connected with links C' of a cross chain. In this view, the construction is substantially the same as the construction of the link 7^a, but heavier material is preferably employed and disconnection of the link 7^b 30 from the links C', may be prevented by bending the bills 10^b of the hooks into close relation with each other instead of slanting them toward the longitudinal body portion of the hook. These bills are provided 35 with sharp-edged calks 12^b which may substantially duplicate either the calks 12 or the calks 12^a, or may in some instances be of other forms.

Regardless of the exact details of construction employed for the link and regardless of the way in which a number of these links are associated with other links, the invention will be efficient to a high degree 40 for preventing skidding and giving ample traction on slippery surfaces. The ways in which the links may be used, are too 45 numerous for illustration in this application, and the applications which have been disclosed, are hence only illustrative of a 50 few ways in which the device may be employed.

There are certain features of construction generic to all forms of the invention herein disclosed. Each form, considered specifically, embodies an elongated substantially central body portion such as 8, return bends such as 9 at the ends of said body portion providing hooks for connecting the link with other links, and calks such as 12 formed on 60 and extending longitudinally of the hook bills, such as 10. Considered even more specifically, each improved link embodies the features just enumerated, plus the transverse V-shape of the link, with one hook and 65 its calk occupying one side of the V, the

other hook and its calk occupying the other side of the V and the longitudinal body portion 8 disposed at the apex of the V. Considered in another aspect, the invention comprises a link of substantially V shape in 70 transverse section and having means at its ends for connecting it with additional links, the portions of the V remote from the apex thereof constituting calks, the aforesaid connecting means being inwardly spaced from 75 a common plane (such as P) at which the road engaging portions of said calks terminate, thus insuring that these calks and not the connecting means shall receive the greater amount of wear. Considered in still 80 another manner, the invention comprises a link composed of an elongated substantially central body portion having means at its ends for connecting it with other links, and road engaging portions extending longitudinally of and diverging laterally from said body portion. In the present disclosure, the body portion just referred to is a formation such as 8, the means at the ends of this body portion for connecting it with other 85 links, are the hooks such as 9, and the road engaging portions extending longitudinally of and diverging laterally from said body portion, are the portions such as 10 and 12. It will be understood however that links may 90 be produced having characteristics such as those briefly defined in this paragraph, without resorting to specific details of construction herein disclosed.

I claim:

1. An anti-skidding link comprising an elongated body having return bends at its ends providing two hooks whose bills extend inwardly toward opposite ends of the link, each of said bills being provided with 105 an integral elongated calk along its lower side extending substantially throughout its length.

2. An anti-skidding link comprising an elongated body having return bends at its ends providing two hooks whose bills extend inwardly toward opposite ends of the link, each of said bills being provided with an integral elongated calk extending longitudinally thereof, said link being of V shape 110 transversely with one of said hooks and its calk occupying one side of the V, the other hook and calk occupying the other side of the V and said body disposed at the apex 115 of the V.

3. An anti-skidding link comprising a short rod having return bends at its ends providing two hooks whose bills extend inwardly toward opposite ends of the link, the end portions of said rod at the ends of 120 said bills being bent upon the latter and extending longitudinally of said bills to provide calks.

4. A structure as specified in claim 3; said link being V-shaped transversely with one 125

of said hooks and its calk occupying one side of the V, the other hook and calk occupying the other side of the V and the central portion of the rod disposed at the 5 apex of the V.

5. An anti-skidding link of substantially V shape in transverse section and having means at its ends for connecting it with additional links, the portions of the V re-
10 mote from the apex thereof constituting calks, said connecting means being inwardly spaced from a common plane at which the

road-engaging portions of said calks terminate.

6. An anti-skidding link comprising an 15 elongated substantially central body portion having means at its ends for connecting it to other links, and road engaging portions extending longitudinally of and diverging laterally in transverse section from said body 20 portion.

In testimony whereof I have hereunto affixed my signature.

FREDERICK MARKWICK.
